UNITED STATES PATENT OFFICE

161,473

TOY AIRPLANE

Sebastian Latina, Detroit, Mich.

Application May 27, 1949, Serial No. 2,909

Term of patent 7 years

(Cl. D34—15)

To all whom it may concern:

Be it known that I, Sebastian Latina, a citizen of the United States, residing at Detroit, in the county of Wayne and State of Michigan, have invented a new, original, and ornamental Design for a Toy Airplane, of which the following is a specification, reference being had to the accompanying drawing, forming a part thereof, in which:

Fig. 1 is a top plan view of the toy airplane, showing my new design;

Fig. 2 is a side elevational view thereof; and

Fig. 3 is a front elevational view thereof.

I claim:

The ornamental design for a toy airplane, substantially as shown.

SEBASTIAN LATINA.
